[57] **CLAIM**

The ornamental design for a multi-function hand tool, as shown.

DESCRIPTION

FIG. 1 is a perspective view of a multi-function hand tool showing my new design, with the jaw in an open position;

FIG. 2 is a front elevational view thereof, with the jaw in a closed position;

FIG. 3 is a rear elevational view of FIG. 2;

FIG. 4 is a left side elevational view of FIG. 2;

FIG. 5 is a right side elevational view of FIG. 2;

FIG. 6 is a top plan view of FIG. 2;

FIG. 7 is a bottom plan view of FIG. 2; and,

FIG. 8 is a front elevational view of FIG. 1.

FIG. 1

FIG. 2

FIG. 8

FIG. 3

FIG. 4

FIG. 5

FIG. 6

FIG. 7
